US0D1099507S

(12) **United States Design Patent** (10) **Patent No.:** **US D1,099,507 S**
(45) **Date of Patent:** **** Oct. 28, 2025**

(54) **SHOE**

(71) Applicant: **adidas AG**, Herzogenaurach (DE)
(72) Inventors: **Andreas Hierl**, Nuremberg (DE); **Rider Anthony Evans**, Nuremberg (DE)
(73) Assignee: **adidas AG**, Herzogenaurach (DE)
(**) Term: **15 Years**
(21) Appl. No.: **29/992,612**
(22) Filed: **Mar. 10, 2025**

Related U.S. Application Data

(63) Continuation of application No. 29/869,636, filed on Jan. 5, 2023, now Pat. No. Des. 1,065,806.

CLAIM

The ornamental design for a shoe as shown and described.

DESCRIPTION

FIG. 1 is a front perspective view of a shoe showing the claimed design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines in the figures and the areas within the broken lines show portions of the shoe that form no part of the claimed design.

The figures show the claimed design in grayscale. The claimed design is not limited to the specific gray coloring shown.

1 Claim, 7 Drawing Sheets
